UNITED STATES PATENT OFFICE.

THEODORE STEIMER, OF FINDLAY, OHIO.

DESIGN FOR A DISH.

SPECIFICATION forming part of Design No. 23,495, dated July 24, 1894.

Application filed February 9, 1893. Serial No. 461,683. Term of patent 7 years.

To all whom it may concern:

Be it known that I, THEODORE STEIMER, of Findlay, in the county of Hancock and State of Ohio, have invented a new and original

5 Design for a Dish, of which the following is a full, clear, and exact description, reference being had to the accompanying drawing, which is a perspective view of a goblet embodying my design.

10 The essential feature of my design consists in a dish or similar article of glassware having a body, a stem, and a flat or spreading foot having radial scallops formed alternately on the upper and lower surfaces of the foot, 15 the scallops tapering from the outer edge of the foot toward the center.

In the drawing, *a* represents the body of a dish in the form of a goblet, *b* the stem, and

c the foot which is provided with radial scallops *d*, situate alternately on the upper and lower faces of the foot and tapering from the outer edge of the foot toward the stem *b*.

I claim—

The design for a dish consisting of the body, stem, and a flat spreading foot having radial scallops situate alternately on the upper and lower surfaces of the foot and tapering toward the center thereof, substantially as shown and described.

In testimony whereof I have hereunto set my hand.

THEODORE STEIMER.
